INVENTOR

UNITED STATES PATENT OFFICE

101,427

DESIGN FOR A DRESS

David Rosenthal, New York, N. Y.

Application September 1, 1936, Serial No. 64,663

Term of patent 3½ years

To all whom it may concern:

Be it known that I, David Rosenthal, a citizen of the United States of America, residing in Manhattan, county of New York, and State of New York, have invented a new, original, and ornamental Design for a Dress, of which the following is a specification, reference being had to the accompanying drawing, forming part thereof, wherein.

The design is characterized by the combination of tassels and braiding in combination with the dress, as shown.

I claim:

The ornamental design for a dress, substantially as shown, and described.

DAVID ROSENTHAL.
